[57] **CLAIM**

The ornamental design for a bottle, as shown and described.

DESCRIPTION

FIG. 1 is a top plan view of a bottle showing my new design;

FIG. 2 is a side elevational view;

FIG. 3 is an elevational view looking from the right of FIG. 2, the opposite side being the same in appearance;

FIG. 4 is a bottom plan view; and

FIG. 5 is a perspective view of the bottle shown in FIGS. 1 through 4;

FIG. 6 is a top plan view showing another embodiment of my new design;

FIG. 7 is a side elevational view of the embodiment shown in FIG. 7;

FIG. 8 is an elevational view looking from the right side of FIG. 7, the opposite side being the same in appearance;

FIG. 9 is a bottom plan view of the embodiment shown in FIG. 6; and

FIG. 10 is a perspective view of the embodiment shown in FIGS. 6 through 9.
